UNITED STATES PATENT OFFICE.

WILLIAM H. WYE, OF NEEDHAM, MASSACHUSETTS.

DESIGN FOR A JACKET.

No. 39,346.

Specification for Design.

Patented June 9, 1908.

Application filed March 19, 1908. Serial No. 422,190. Term of patent 7 years.

To all whom it may concern:

Be it known that I, WILLIAM H. WYE, a citizen of the United States, residing at Needham, in the county of Norfolk and State of Massachusetts, have invented a new, original, and ornamental Design for Jackets, of which the following is a specification, reference being had to the accompanying drawing, forming a part thereof.

Referring to the drawing Figures 1 and 2 are respectively a front and rear view showing my new design for a jacket.

I claim—

The ornamental design for a jacket as shown.

WILLIAM H. WYE.
